UNITED STATES PATENT OFFICE.

EDWIN E. ZERKLE, OF CHICAGO, ILLINOIS.

RESPIRATORY APPARATUS.

No. 909,979.

Specification of Letters Patent.

Patented Jan. 18, 1909.

Application filed January 21, 1908. Serial No. 411,975.

To all whom it may concern:

Be it known that I, EDWIN E. ZERKLE, a citizen of the United States, residing at Chicago, in the county of Cook and State of Illinois, have invented certain new and useful Improvements in Respiratory Apparatus, of which the following is a specification.

In treating tuberculosis and kindred diseases of the respiratory tract, it has been demonstrated that the most effective method of alleviation or cure is fresh air treatment.

It is the object of my invention to construct a respiratory apparatus which will conduct the fresh air from without to a person within, the admitted air being not only filtered and purified but also reduced to the proper temperature through the instrumentality of an air supply chamber hereinafter referred to. This apparatus is especially adapted for use in hospitals as well as dwellings, and is calculated to produce beneficial results to invalids and sick persons, as well as those merely threatened with disease.

The invention consists in the features of construction and combination of parts hereinafter described and claimed.

In the drawings, Figure 1 is a side elevation of my improved respiratory apparatus in use; Fig. 2 a vertical sectional elevation of said apparatus; and Fig. 3 a transverse section taken on line 3-3 of Fig. 2 looking in the direction of the arrow.

My improved respiratory apparatus comprises an inlet air supply pipe 4, having a part of its free end 5 provided with a number of perforations 6; over which a suitable screening 7, having preferably a very fine mesh, is spread. This air supply pipe or passage, when in use, is adapted to have its free outer end projected into the open air in any suitable manner, and it will be seen that the construction is such as to filter, in a measure, all air passing in and through the inlet air supply pipe or passage aforesaid. When this inlet pipe is projected through a window opening, as indicated in Fig. 1, it is desirable to make the opening about the window casing air tight, and the inlet pipe is accordingly mounted between upper and lower transverse supports 8 and 9, respectively, positioned within the window casing, forming, in effect, an air tight wall, the upper transverse section 8 contacting, on its upper side, the raised window 10. Upon the inner end 11 of this inlet air supply pipe

is secured an air conveying tube 12, which may be made of rubber or other suitable material, having its other end retained about a nipple 13 communicating with an air supply chamber 14, usually of spherical formation. Another air filter 15 is placed within the nipple 13 aforesaid, as indicated in Fig. 2, in order to subject the flowing air to a second filtration prior to being admitted to the air supply chamber. The filter 15 is of somewhat finer mesh than that on the outer supply pipe aforesaid. This spherical air supply chamber 14 can be made of copper or other material capable of being readily influenced by the extraneous atmospheric conditions in the room within which it is placed. The reason for this is that the temperature of the admitted flowing air will be modified from time to time, thus eliminating, in a measure, any undue chill contained therein. This air supply chamber can be retained in place by a bracket 16, or in any suitable manner, as indicated in Fig. 1. An outlet port or passage 17 is formed, as shown, at the bottom of the spherical air supply chamber, and has a membrane or any other suitable form of valve 18.

A depending nipple 21 is adapted to receive thereon a flexible air supply tube 22 which terminates, at its other end, in a rigid face mask 23. This mask is especially designed to be placed upon the face of a person, as illustrated in Fig. 1, and is concave in cross section, being provided with suitable cushioning means 24, which may consist of pneumatic rubber cushions, felt, or other material. It is essential, however, that the face mask fit snugly, and experience has shown that a pneumatic rubber cushion gives the best results. Formed on the top of this face mask is an ordinary disk valve 25, which permits the exhaled air to escape therefrom. Straps or bands 26, as usual, are secured to the face mask for the purpose of enabling the same to be fastened thereto. This method of communication between the air supply chamber and the face mask does away with the inconvenience incident to the use of this form of apparatus, in that it permits the patient to freely move about in his room or bed as the flexible air supply tube adjusts itself to any position within its radii. The smallness of the face mask is necessary in order to do away with all air not actually used by the patient.

In use, the apparatus as a whole having

been positioned, the mask is fastened about the person's face, and the same being air tight, as before stated, a suction will be produced, by the breathing action of the person, in the air supply pipe 22, which in turn influences the action of the flap valve aforesaid, permitting fresh air to be drawn from the air supply chamber down through said tube to the mask, where it is inhaled, and when exhaled is permitted to escape through the disk valve 25 aforesaid.

From the foregoing it will be apparent that my improved device does away with the objection found to fresh air treatments now in use, in that the injurious effects produced from excessive chill in the air in cold weather is modified and eliminated in a large measure and the fresh air, as conducted to the user, produces the same beneficial results as if the person inhaling the same were out of doors. In fact, my respiratory apparatus is a marked improvement over those now used, because it is capable of supplying fresh air at suitable temperature to invalids or those incapable of going outside, and the mask is constructed so as to permit the user to freely move about in bed without disturbing the operation thereof.

What I claim as new and desire to secure by Letters Patent is:

1. A respiratory apparatus, comprising an air supply pipe in communication with the outer air and an air supply chamber, means for filtering the admitted air, a shell formed of thin material, sensitive to the effects of heat and cold, and inclosing a chamber for supplying air, said chamber having inlet and outlet passages, means for withdrawing air from the air supply chamber, and a face mask provided with a discharge valve, substantially as described.

2. A respiratory apparatus, comprising an air supply pipe in communication with the outer air and an air supply chamber, said air supply pipe being provided with means for filtering the flowing air, a shell formed of

thin material, sensitive to the effects of heat and cold, and inclosing a chamber for supplying air, said chamber having inlet and outlet passages, a valve closing the outlet passage in the air supply chamber, an air conducting tube in communication with the outlet passage of the air supply chamber, and a face mask provided with a discharge valve, substantially as described.

3. A respiratory apparatus, comprising an air supply pipe in communication with the outer air and an air supply chamber, means for filtering the admitted air, a shell formed of thin material, sensitive to the effects of heat and cold, and inclosing a chamber for supplying air, said chamber having inlet and outlet passages, nipples extending from said inlet and outlet passages, a valve normally closing the outlet passage, an air conducting tube in communication with the outlet passage, and a face mask provided with a discharge valve, an air tight cushion, and straps for securing the same upon a person's face, substantially as described.

4. A respiratory apparatus, comprising an air supply pipe in communication with the outer air and an air supply chamber, air tight means for positioning the outer end of the air supply pipe outside of a window, a shell formed of thin material, sensitive to the effects of heat and cold, and inclosing a chamber for supplying air, said chamber having inlet and outlet passages, means for filtering the admitted air, means for withdrawing air from the air supply chamber, and a face mask provided with a discharge valve, substantially as described.

5. In a respiratory apparatus, a shell formed of thin material, sensitive to the effects of heat and cold, and inclosing a chamber for supplying air, substantially as described.

EDWIN E. ZERKLE.
